CAN AGITATOR

Frank D. Chapman, Berlin, Wis.

Application January 12, 1935, Serial No. 1,541

10 Claims. (Cl. 253—49)

The present invention relates in general to improvements in the art of treating hermetically sealed batches of commodity, and relates more specifically to improvements in the construction and operation of receptacle-shaking or agitating apparatus especially adapted to facilitate the heat treatment of products confined within containers.

Generally defined, an object of the invention is to provide an improved receptacle shaker or agitator, which is simple in construction and efficient in operation.

It has heretofore been proposed, as shown and described in my prior Patent No. 1,975,073, granted October 2, 1934, to provide a can agitating sterilizer comprising a movable support, means for moving the support to endwise reciprocate an annular series of food-laden cans along the axis of annularity of the series, and means for displacing the series of cans about the said axis. While this prior agitator has proven highly practical in actual commercial use, it is relatively difficult to load and to unload the machine, and, also, the prior device lacks capacity when large numbers of cans are to be treated.

It is therefore a more specific object of the present invention to provide various improvements in the details of construction of machines of the general type forming the subject of said patent, whereby the operation and use of such devices is facilitated, and the efficiency thereof is enhanced.

Another specific object of the present invention is to provide an improved can agitator, which may be quickly and conveniently loaded or unloaded, and wherein the receptacles are firmly held in position during the shaking operation.

A further specific object of the invention is to provide a durable agitating sterilizer having maximum capacity for minimum space occupied by the apparatus, and which can be actuated with minimum power consumption.

Still another specific object of the invention is to provide an improved can-shaking mechanism which is cooperable with containers of various sizes and shapes; and which can be readily manipulated to obtain most effective and desirable results.

These and other objects and advantages of the invention will be apparent from the following detailed description.

A clear conception of embodiments of the various improved features, and of the mode of constructing and of operating can agitators built in

accordance with the invention, may be had by referring to the drawings accompanying and forming a part of this specification, in which like reference characters designate the same or similar parts in the various views.

Fig. 1 is a perspective view of a double agitating sterilizer as it appears during normal operation, and also showing a crate loading truck in cooperative relation with one of the agitator units;

Fig. 2 is an enlarged, longitudinal section through the main casing of one of the agitator units with the foremost can-carrying crate omitted therefrom;

Fig. 3 is an end view of the agitator unit shown in Fig. 2, looking toward the loading end of the main casing;

Fig. 4 is a transverse, vertical section through the unit of Fig. 2, taken just inside of the loading end of the main casing and showing the rotor 20 completely filled with crates;

Fig. 5 is a further enlarged, part sectional, top view of one of the can-carrying crates, showing the manner in which these crates are loaded into and confined within the sterilizer;

Fig. 6 is a part sectional side view of the can-carrying crate of Fig. 5;

Fig. 7 is a part sectional end view of the crate, looking toward the resilient clamping mechanism for confining the cans against endwise displacement;

Fig. 8 is a part sectional, opposite end view of the crate, looking toward the handling end thereof and showing the wood spacer and cans removed;

Fig. 9 is a still further enlarged, central, vertical section through the resilient can clamping structure carried by each crate;

Fig. 10 is a likewise enlarged, fragmentary end view of the crate locking mechanism;

Fig. 11 is a fragmentary side view of the crate locking structure of Fig. 10;

Fig. 12 is a side elevation of one of the crate loading and handling trucks, showing a crate positioned horizontally thereon;

Fig. 13 is a similar view of the truck, showing the crate swung to substantially upright loading position; and

Fig. 14 is an end view of the loading and handling truck, showing the crate positioned as in Fig. 12.

While the invention has been illustrated and described herein as being specifically applied to an agitating sterilizer for heat treating batches

of food-laden, cylindrical cans in succession, it is not intended to unnecessarily restrict the scope by such specific embodiment; and it will be apparent that some of the improved features may be more generally applied with advantage to other types of apparatus.

Referring to Figs. 1 to 4, inclusive, of the drawings, the improved can-agitating sterilizer comprises in general a base 15 having one or more cylindrical retorts or main casings 16 fixedly supported thereon; a can crate supporting rotor 17 both slidably and rotatably mounted within each casing 16 by means of a main central shaft 18 supported in front and rear bearings 19, 20, respectively; mechanism 21 associated with the portion of each shaft 18 adjacent to the front bearing 19 thereof, for reciprocating the corresponding rotor 17 longitudinally of its axis and within its confining casing 16; and other mechanism cooperating with the opposite end portion of each shaft 18 near the bearing 20, for effecting revolution of each rotor about its axis, either while the rotor is at rest or during normal reciprocation thereof.

Each main casing 16 has a loading and unloading end head 21 provided with a door 22 disposed laterally of the shaft 18, and each door 22 is adapted to be locked in closed position by means of levers 23 and manually operable jack-screws 24 coacting therewith. The retorts or casings 16 may also be provided with suitable means for heating the interiors thereof, and for controlling the temperatures therein, and the heating and pressure control systems for these units are well known to those skilled in the art and constitute no part of the present improvement.

The present improved can-supporting and agitating rotor 17 is built up of a plurality of metallic structural members to form an annular series of four crate receiving and retaining compartments spaced about the central supporting shaft 18 as shown in Figs. 2 and 4, and each having a series of crate engaging rollers 25 at one side thereof. The crate receiving compartments of the rotor 17 are of slightly smaller transverse, cross-sectional area than the opening in the end head 21 with which the door 22 coacts, and a stop plate 26 is rigidly attached to the rotor 17 centrally at the end of each compartment remote from the end head 21. The opposite end of the rotor 17 adjacent to each of the crate confining compartments is provided with a pivoted locking bar 27 having its swinging end constructed as shown in Figs. 10 and 11, these bars being swingable as shown in dotted lines at the top of Fig. 4, in order to permit insertion and removal of crates to and from the compartments. The swinging end of each latch bar 27 is notched for engagement with a tie rod and latching bolt 28 and is adapted to be locked in engagement with the bolt 28 by means of a retainer 29 which is snapped into locking position by a spring 30 and is manually releasable upon compression of this spring, to permit the bar 27 to be swung away from its bolt 28. In Fig. 10, the retainer 29 is shown in released position, and in Fig. 11, the retainer has been snapped into locking position with its opposite end portions in locking engagement with notches 31 formed in the end of the bar 27.

One of the improved can confining crates 32 is shown in detail in Figs. 5, 6, 7, and 8 and comprises an elongated, rectangular box-like structure having an open side, and a plurality of perforations 33 in the other longitudinal side walls,

One end wall of each crate 32 is provided with a central opening 34 and is normally engaged by a plate 35, shown in detail in Fig. 9, which has a tubular casing 36 attached thereto and projecting through the opening 34 in the end wall of the 5 crate. A cap 37 secured to the tubular casing 36 slidably supports a plunger 38 which is constantly urged outwardly by a coil spring 39 confined within the casing 36, and the outer end of this plunger 38 is adapted to engage an adjacent reaction plate 26 of the rotor 17 when the crate 32 is pushed longitudinally within one of the crate receiving compartments. The crate 32 is, moreover, provided with corner rails 40 formed of angle irons, which are adapted to engage the 10 rollers 25 of the rotor 17 during insertion and removal of the crate 32; and the end wall of the crate remote from the plate 35 thereof is provided with a manipulating handle 41 and with a stiffening plate 42 as shown in Figs. 4, 6, and 8. Each 15 crate 32 may also be provided with side lugs 43 for facilitating carriage thereof by means of side hooks and a crane, but these are not essential; and the free edges of the walls of each crate 32, which are nearest the crate loading opening, are 20 preferably reinforced by a band 44.

Each crate 32 is adapted to receive a series of can confining trays 45 which are provided with perforations 46 and are capable of receiving cans 47 of various sizes. The trays 45 are of less 25 height than the cans 47 and may be inserted into and removed from the crate 32 through the open side thereof. A wooden filler block 48 may be utilized to fill the space adjoining the end wall 30 of the crate 32, which is uppermost during loading, so that each crate will be substantially filled with the trays 45 and cans 47, when properly loaded, as clearly shown in Figs. 5 and 6.

The individual crates 32 may be conveniently 35 loaded and unloaded by mounting the same upon a special truck 49 having a pivotally suspended 40 crate cradle or support 50, as shown in Figs. 1, 12, 13, and 14. The truck 49 has supporting 45 wheels 51 which permit convenient transportation thereof, and the support 50 is secured to the truck 49 by aligned pivots 52 and is swingable from substantially horizontal position, as in Figs. 12 and 14, to substantially upright loading position, as in Figs. 1 and 13, the pivots 52 being set to bias 50 the support 50 toward horizontal position and against a stop 53. The downwardly swingable end of the cradle support 50 has a removable crate 55 stop bar 54 and a hook latch 55 for holding the support 50 in substantially upright loading position, and the support 50 also has rollers 56 co-operable with the crate rails 40 so as to permit ready sliding of the crates 32 onto and off of the truck cradle. When the crate 32 and support 50 are positioned as illustrated in Fig. 13, the can 60 filled trays 45 may be stacked within the crates or removed therefrom with the greatest of ease; and when the cradle is swung into horizontal position, the bar 54 may be removed and the crate 32 may then be pushed off of the cradle and into 65 the rotor crate receiving compartments past the door 22 of the casing 16, in an obvious manner.

In order to effect locking of the loaded crates 32 within the rotor 17, after they have been inserted in the manner just described, a special 70 form of jack mechanism shown in Figs. 5 and 6 may be employed. When a loaded crate 32 has been pushed into position with the end plunger 38 in engagement with the corresponding plate 26, the jack yoke 57 may be applied to the in- 75

terior surface of the casing end head 21 at opposite sides of the inlet opening; and a jack screw 58, adjustably mounted within the yoke 57, may be brought into engagement with the reenforcing end plate 42 by turning the jack handle 59. The crate 32 may then be forced forwardly to compress the spring 39 coacting with the plunger 38 and with the end plate 35, and the cans 47 and trays 45 are thus clamped against possible endwise displacement. When sufficient compression of the spring 39 has been effected, the corresponding pivoted locking bar 27 may be swung across the adjacent end of the crate and latched in position by manipulating the latch device 29. Upon subsequent release and removal of the special jack, the spring 39, coacting with the plunger 38, will become effective to force the crate 32 into firm engagement with the cross-bar 27, and to clamp the trays 45 and cans 47 against endwise displacement relative to the rotor 17 during reciprocation of the latter. The crates 32 may obviously be removed from the rotor 17 by again utilizing this special jack and by reversing the loading operation, and the tie rods or bolts 28, which also serve to enhance the rigidity of the rotor structure, function to facilitate effective clamping of the crates 32, trays 45, and cans 47 within the rotor compartments.

The rotor 17 may be readily revolved to permit loading and unloading of the rotor compartments, by mechanism associated with the casing end head 21, as shown in Figs. 1, 2, and 3. This mechanism, which also serves to revolve the rotor 17 during reciprocation thereof while the canned product is undergoing treatment, comprises gearing 60 carried by a bracket 61 and operable by power applied to a pulley 62. If so desired, a hand wheel 63 may also be provided for manual actuation of the gearing, and this mechanism for revolving the rotor 17 may be substantially the same as that shown in my prior patent hereinabove referred to. The mechanism 21' for reciprocating the rotor 17 during heat treatment of the product may likewise be similar to that of my prior patent, and as shown in Fig. 1, the weight of one loaded rotor may be utilized to substantially counter-balance that of another, during reciprocation thereof, in order to avoid necessity of employing a counter-weight for such balancing purposes. This double arrangement of the agitating units also enhances the capacity and reduces the power consumption to a minimum.

While the normal use of the apparatus should be relatively apparent from the foregoing detailed description thereof, the following is a short resume of such normal use. In order to load one of the crates 32 with hermetically sealed, food-laden cans 47, it is only necessary to place the crate upon the movable support 50 of the loading truck 49 and to swing this support into the position indicated in Fig. 13. The stop bar 54 serves to retain the crate 32 upon the support 50, and the open side of the crate is then accessible for insertion or removal of the can-laden trays 45. When the crate has been loaded with trays 45 and cans 47, the latch 55 may be released, whereupon the support 50 may be tilted to horizontal position against the stop 53. The truck 49 may then be transported to a position of alinement with the opening in the end head 21 of one of the casings 16, and upon opening the door 22, the loaded crate 32 may be pushed off of the rollers 56 of the support 50 and into one of the rotor compartments.

After the crate has been pushed into the rotor compartment, with the plunger 38 thereof in engagement with the corresponding rotor stop 26, the special jack may be applied for the purpose of clamping the cans 47 and the trays 45 within the crate 32. The yoke 57 of this special jack may be inserted through the open doorway and applied to the end head 21, after which the jack screw 58 may be brought forwardly against the plate 42. When the spring 39 has been sufficiently compressed to permit the locking bar 27 to be swung across the adjacent end of the crate 32, this bar may be brought into effective position and locked in place with the aid of the latching device 29. The special jack may be subsequently removed, and during such removal of the jack the spring 39 will force the trays 45 and cans 47 against the rear end of the crate 32 and will, in turn, force this rear end into intimate engagement with the cross-bar 27, thereby firmly clamping the trays and cans against possible endwise displacement relative to the crate.

When the rotor 17 has been completely loaded with can-laden crates 32, the door 22 may be sealed, whereupon the interior of the casing 16 may be supplied with suitable heating medium. The cans 47 are then agitated by reciprocation of the rotor 17 with the aid of the mechanism 21, and the rotor 17 may be simultaneously rotated by applying power to the driving pulley 62, which actuates the gearing 60. After the confined product has been sufficiently heat treated, removal of the cans may be effected by opening the door 22 and subsequently utilizing the special jack to release the successive locking bars 27. The crates 32 may then be withdrawn upon the support 30 of a truck 49 and may be conveyed by means of this truck to cooling baths. The lugs 48 facilitate removal of the hot crates 32 from the truck, and if so desired, the crate 32 may again be unloaded by utilizing a truck 49 for that purpose.

From the foregoing description it will be apparent that the present invention provides simple, compact, and highly efficient means for facilitating loading and unloading of an agitator of the general type described. The crates 32 and trays 45 are preferably perforated so as to permit efficient application of the heating medium to the cans 47, and the mode of clamping these cans within the crates 32 prevents possibility of injury to the cans due to endwise displacement thereof while the rotor is being reciprocated. By utilizing crates 32, the rotor 17 may be quickly loaded and unloaded with minimum loss of time; and the improved truck 49 obviously facilitates loading and unloading of the individual crates with trays 45. The improved features have proven highly successful in actual commercial operation, and by utilizing opposed units, as illustrated in Fig. 1, the capacity and efficiency of this type of apparatus can be further enhanced.

It should be understood that it is not desired to limit the invention to the exact details of construction and to the precise mode of operation herein shown and described, for various modifications within the scope of the claims may occur to persons skilled in the art.

It is claimed and desired to secure by Letters Patent:

1. In combination, a support having an axis, means for reciprocating said support along said axis, a crate adapted to be mounted upon said support, a plurality of receptacle confining trays formed for stacked assembly within said crate

and along said axis, and means carried by said crate and cooperating directly with said support when said crate is mounted thereon for clamping said trays and the receptacles therein so as to prevent displacement of said crate, trays and receptacles relative to said support when the latter is reciprocated.

2. In combination, a support having an axis, means for reciprocating said support along said axis, means for effecting angular displacement of said support about said axis, a crate adapted to be mounted upon said support, a plurality of receptacle confining trays formed for stacked assembly within said crate and along said axis, and means carried by said crate and cooperating directly with said support and with one of said trays when said crate is mounted upon said support for clamping said trays and the receptacles therein so as to prevent displacement of said crate, trays and receptacles along or away from said axis and relative to said support when the latter is reciprocated or displaced about said axis.

3. In combination, a support having an axis, means for effecting angular displacement of said support about said axis, a crate adapted to be mounted upon said support, a plurality of receptacle confining trays formed for stacked assembly within said crate and along said axis, and means carried by said crate and cooperating directly with said support when said crate is mounted thereon for clamping said trays and the receptacles therein so as to prevent displacement of said crate, trays and receptacles relative to said support when the latter is angularly displaced.

4. In combination, a support having a substantially horizontal axis, means for reciprocating said support along said axis, means for effecting angular displacement of said support about said axis, a series of elongated crates adapted to be mounted upon said support around said axis, a plurality of receptacle confining trays formed for stacked assembly within each of said crates and along said axis, and resilient means carried by each of said crates and cooperable directly with said support when said crates are mounted upon said support for clamping all of said trays and the receptacles therein so as to prevent displacement of said crates, trays and receptacles relative to said support when the latter is reciprocated or angularly displaced.

5. In combination, a support having an axis and a series of compartments disposed around said axis, means for reciprocating said support along said axis, a series of crates adapted to be inserted within said compartments substantially parallel to said axis, a plurality of receptacle confining trays formed for stacked assembly within each of said crates and along said axis, and resilient means carried by each of said crates and cooperable directly with said support when said crates are disposed within said compartments for clamping all of said trays and the receptacles therein against displacement relative to said support when the latter is reciprocated.

6. In combination, a wall having an opening therein, a support having an axis and a compartment registrable with said opening, a crate adapted to be inserted within said compartment through said opening, a plurality of receptacle confining trays formed for stacked assembly within said crate and along said axis, resilient means carried by said crate and cooperable directly with said support when said crate is in-

serted within said compartment, means cooperable with said wall after said insertion for compressing said resilient means to effect clamping of said trays and the receptacles therein within said crate, and means for effecting displacement of said support relative to said axis.

7. In combination, a fixed wall having an opening therein, a support movable relative to an axis and having a compartment registrable with said opening, a crate formed for insertion within said compartment only through said opening, a plurality of receptacle confining trays formed for stacked assembly within said crate and along said axis, resilient means at one end of said crate and cooperable with said support when said crate is inserted within said compartment, means cooperable with said wall after said insertion for compressing said resilient means to clamp said trays and receptacles within said crate, means for subsequently locking said trays and receptacles in clamped condition, and means for moving said support relative to said axis.

8. In combination, a wall having an opening therein, a support movable relative to said wall and having a compartment registrable with said opening, a crate adapted to be inserted within said compartment only through said opening, a plurality of receptacle confining trays formed for stacked assembly within said crate, a resilient plunger at one end of said crate and cooperable with said support when said crate is inserted within said compartment, a jack cooperable with said wall after said insertion for compressing said plunger to clamp said trays and receptacles within said crate, a latch at the opposite end of said crate for subsequently locking said trays and receptacles in clamped condition and for retaining said crate in fixed position relative to said support, and means for moving said support.

9. In combination, a wall having an opening therein, a support movable about an axis and having a series of compartments disposed about said axis and successively registrable with said opening, a series of crates adapted to be inserted within said compartments only through said opening, a plurality of receptacle confining trays stacked within each of said crates, a resilient plunger carried by an end of each of said crates and cooperable with said support when the crate is inserted within one of said compartments, a jack cooperable with said wall after insertion of each crate within a compartment for compressing said plunger to clamp said trays and receptacles within said crates, and a latch cooperable with the opposite end of each crate for locking said crates, trays and receptacles against displacement relative to said support when said jack has been removed.

10. In combination, a fixed wall having an opening, a movable support having a compartment registrable with said opening, a crate insertable within said compartment through said opening, receptacle confining trays stacked within said crate, a spring pressed plunger carried by one end of said crate and cooperable with said support when the crate is inserted within said compartment, a jack cooperable with said crate and with said wall after said insertion to compress the plunger spring and thereby clamp said trays and receptacles within said crate, and a latch cooperable with the opposite end of said crate for locking said crate, trays and receptacles within said compartment.

FRANK D. CHAPMAN.
